DESIGN FOR A HANDBAG FRAME

Harry Morris, Chicago, Ill.

Application November 15, 1945, Serial No. 123,757

Term of patent 14 years

(Cl. D87—2)

To all whom it may concern:

Be it known that I, Harry Morris, a citizen of the United States, residing in Chicago, in the county of Cook and State of Illinois, have invented a new, original, and ornamental Design for a Handbag Frame, of which the following is a specification, reference being had to the accompanying drawing, forming part thereof.

Fig. 1 is a perspective elevational front view of a handbag frame in unlocked position showing my design,

Fig. 2 is a rear perspective elevational view in unlocked position, of the handbag frame shown in Fig. 1.

Fig. 3 is a front elevational view of the handbag frame in locked position, and

Fig. 4 is the rear view thereof.

I claim:

The ornamental design for a handbag frame, substantially as shown.

HARRY MORRIS.
